TRAINING DEVICE FOR BOWLING ALLEY

Len Casey, 5924 SW. 68th St.,
South Miami, Fla. 33143

Filed July 18, 1972, Ser. No. 272,941

Term of patent 14 years

Int. Cl. D21—02

U.S. Cl. D34—5 DD

FIG. 1

FIG. 2

FIG. 3

FIG. 4

FIG. 1 is a front elevation in reduced scale, of a training device for bowling alley, showing my new design.

FIG. 2 is a side elevation thereof.

FIG. 3 is a top plan view thereof.

FIG. 4 is a bottom plan view thereof.

The side not shown is the same as that shown in FIG. 2.

I claim:

The ornamental design for a training device for bowling alley, as shown and described.
